Inventor:
Albert Cotic
By William H. Young.
ATTORNEY

UNITED STATES PATENT OFFICE.

ALBERT COTIC, OF HERBRECHTINGEN, GERMANY.

SPINDLE BOLSTER FOR ROVING MACHINES.

Application filed October 20, 1926, Serial No. 142,972, and in Germany October 24, 1925.

This invention relates to a bolster for the spindles of roving machines, and more particularly to that type of machine in which the bolster is moved upwardly and downwardly with the copping rail, whilst the flyer together with the spindle executes merely a rotary movement. The bearing portion between the bolster and the flyer spindle is the part of a roving machine which is most subjected to rapid wear, and which causes the greater portion of any irregularity in the run of the machine, the bearing having hitherto been constructed as a simple sliding bearing.

During the rotation of the spindle the bolster, which is mounted on the copping rail, moves slowly in an upward and downward direction. This movement causes the lubricant to be gradually scraped off from the spindle, particularly if the bearing has already been widened due to friction. The lubricating agent is then able to move downwardly along the spindle without obstruction. The spindle accordingly runs unevenly, so that not only a knocking or vibration in the machine is caused, but the quality of the yarn is also affected.

This drawback, according to the invention, is avoided by the provision of rollers, which are situated in recesses in the bolster. The spindle rests against these rollers, the latter being prevented from falling out towards the outside by means of a hood, whilst the recesses are tapered off towards the inside for the purpose of holding the rollers in this direction.

The invention is illustrated by way of example in the accompanying drawing, in which

Fig. 1 is a longitudinal section (with part in full) of the roving machine.

Fig. 2 is a longitudinal section through the upper part of the bolster, on enlarged scale, and

Fig. 3 is a section on the line III—III of Fig. 2.

Referring to the drawing, 1 is the copping rail, which is moved upwardly and downwardly by the wheel and rack gear 2, and on which is mounted the bolster 3. The spool 4, on which the cop 5 is wound, is operated by the copping rail in the known manner. The flyer spindle 6 is passed through

the bolster 3, and carries at the upper end the flyer 7 for supplying and forming the thread, the spindle 6 being rotated at its lower end by the gearing 8. As shown in Figs. 2 and 3, recesses 9 are provided in the upper part of the bolster, and these recesses are tapered towards the longitudinal centre axis. The bolster 3 is set off at 10, and is surrounded at the upper part by a hood 11. Freely revoluble in the recesses 9 are rollers 12, which towards the inside are held by the tapering walls of the recesses, and towards the outside by the hood 11. These recesses in which the rollers are mounted are filled with a consistent grease.

Upon the rotation of the spindle 6 within the bolster rolling friction is thus caused at the bearing points between the spindle and the rollers, whilst due to the generous provision of grease the rollers roll in the recesses. The total resistance due to friction is considerably less than in the case of the known arrangement, and it is quite unnecessary to frequently renew the lubricating agent to such extent as was hitherto the case. The rollers, when the same have been worn down, may be exchanged in very simple manner.

The arrangement described in the above also has the advantage that the bolsters hitherto in use, which have been widened out by friction, may be remodeled, as described above, to form a bolster according to the invention.

What I claim as new and desire to secure by Letters Patent is:

1. A bolster for the spindles of roving machines, having a portion of its circumference cut in, recesses in said cut-in portion of the bolster, rollers in said recesses and contacting the spindle, and a removable hood on said cut-in portion of the bolster for preventing the rollers from falling outwardly, the recesses being tapered inwardly toward the spindle to prevent the rollers from falling inwardly.

2. A bolster for the spindles of roving machines as recited in claim 1 wherein the removable hood has a thickness equal to the depth of the cut-in portion of the bolster.

In testimony whereof I have affixed my signature.

ALBERT COTIC.
